[57] CLAIM

The ornamental design for a hand-held computer, as shown and described.

DESCRIPTION

FIG. 1 is a top, front and left side perspective view of a hand-held computer showing my new design;

FIG. 2 is a top plan view thereof;

FIG. 3 is a right side elevational view thereof, the left side being a mirror image;

FIG. 4 is a rear elevational view thereof,

FIG. 5 is a top plan view thereof; and

FIG. 6 is top and left side perspective view thereof.

The bottom of the hand-held computer is plain and unornamented.
The broken line showings in FIGS. 5 and 6 are for illustrative purposes only and form no part of the claimed design.

FIG. 2

FIG. 1

FIG. 3

FIG. 5

FIG. 4

FIG. 6
